PLUG

Anthony J. Godare, Denver, Colo.

Original application October 15, 1931, Serial No. 569,023. Divided and this application November 17, 1934, Serial No. 753,525

1 Claim. (Cl. 173—322)

This application is a division of an application filed by me October 15, 1931, Serial No. 569,023, now Patent No. 1,990,687, issued Feb. 12, 1935.

The invention relates to devices for closing electric circuits and particularly to plugs and plug receptacles whereby current conductors may be fitted into supply points to receive current therefrom, the object being to provide a construction which will require the plug to be presented to the receptacle in a certain definite position in order to be inserted, and to provide means whereby the strands of the conducting cable will be held separated within the body of the plug so that short circuits will be avoided. The invention is illustrated in the accompanying drawing and consists in certain novel features which will be hereinafter first duly described and then definitely claimed.

In the accompanying drawing,

Fig. 1 is a view showing the plug in side elevation and the receptacle in vertical section,

Fig. 2 is a bottom plan view of the plug,

Fig. 3 is a section on the line 3—3 of Fig. 2.

The reference numeral 1 indicates the lower section of a receptacle body upon the upper side of which an upper section 2 is placed and secured, both sections being formed of some insulating material. The lower section 1 has its bottom end somewhat reduced in diameter and is equipped externally with a collar 3 of metal which is corrugated so as to form threads whereby it may be fitted into an ordinary socket. At one point, the collar or rim 3 has an extension, indicated at 4, which is bent to fit under the body of the plug and be connected to one end of the shank 5 of a contact member. It will be understood, of course, that two contact members are provided in the body of the receptacle and the shanks thereof are received within slots 6 which extend through the lower end of the body section 1 and have their upper portions expanded to form chambers 7, as shown. These chambers 7 are flared upwardly, as shown in Fig. 1 and have their greater dimensions disposed at right angles. The shank of one contact member is extended beyond the end of the body and passes through a washer or plate 8 of insulation and is then bent laterally to extend under said washer or plate, its extremity being provided with an opening 9 through which a securing screw 10 is passed, said screw passing through a central opening in the washer and engaging in an opening provided therefor in the lower end of the plug body, as clearly shown in Fig. 1. The head of the screw 10 constitutes a center contact and the collar 3 constitutes a rim

contact to engage cooperating contacts when the plug is fitted into a socket in the usual manner.

Formed with the upper end of the metallic shank 5 of the contact member are jaws 11 which are resilient so that they tend constantly to press together at their free ends, said ends being formed into eyes or sleeves 12, the axes of which are parallel. To supplement the resiliency of the jaws 11 and to insure a proper contact between the sleeves and an inserted prong, I provide a torsion spring 13 which is formed into a coil between its ends and seated between the lower ends of the jaws.

The contact members, including the shank 5 and the jaws carried thereby, are somewhat longer than the section 1 of the plug body so that the jaws project through the end of the body from the chambers 7. The upper section 2 of the plug body is a circular disk having openings 14 therethrough arranged at a right angle to each other and consisting of slots of proper size to admit and guide the tines or prongs of the plug. The slots 14 open through the upper side of the disk 2 and in the underside of the disk are recesses or chambers 16 which are arranged to align with the chambers 7 and receive the upper ends of the jaws 11 of the housed contact members. The disk or upper body member 2 is secured firmly upon the lower body member 1 upon the lower body member by screws or other fastening means.

The plug comprises a body 18, of insulation, having a passage 19 therethrough for the reception of a cord or cable 20 which is to carry the current to the point of use. Disposed diametrically across the lower end of the plug is a bar 21 of insulating material which is received snugly in a slot or groove provided therefor in the body of the plug, as shown in Figs. 2 and 3. Near the center of this bar 21, openings, indicated at 22, are formed therethrough and the strands 23 of the cable are passed through these openings in opposite directions so as to be held in spaced relation, the ends of the strands being secured by binding or clamping screws 24 to conductor plates 25 which are formed integral with the upper ends of 45 tines or prongs 26 which are located at opposite sides of the bar 21 and project from the end of the plug. It will be noted that the bar 21 serves to separate the tines or prongs so that there can be no short circuit established between them and 50 also separate the plates which form the means for connecting the tines to the plug body. The bar 21 is disposed obliquely with respect to the tines for defining relatively large chambers for the tines and connecting plates so that the con- 55

ducting strands may be easily connected with the plates. The bar, moreover, takes the strain of the conducting cords 23 off the binding screws. The conducting strands are preferably covered 5 with the usual insulating wrapping but this wrapping frequently wears in the ordinary plug now in general use and short circuits have occurred through accidental meeting of the strands. This cannot occur in the plug of my invention. The 10 plates 25 are preferably formed integral with the tines and are held in place in the plug by securing screws 27 as well as by the binding screws 24 which secure the ends of the conductor strands.

Upon reference to Fig. 1, it will be seen that the 15 tines or prongs 26 are disposed at a right angle to each other corresponding to the arrangement of the slots 14 and of the contact members within the receptacle. The extremities of the tines or prongs are tapered, as shown at 28, whereby 20 they may readily enter between the sleeves 12 at the ends of the jaws 11 and, adjacent their tapered ends, notches 29 are formed in the edges of the tines so that, when the plug is inserted, the sleeves or eyes 12 will be engaged in the notches 25 and will resist withdrawal of the plug. A very firm electrical connection between the tines and the contact members in the receptacle is thereby attained and accidental release of the plug is avoided, although the plug may be easily withdrawn when a proper force is applied thereto.

From the foregoing description, taken in connection with the accompanying drawing, it will be seen that I have provided a means for taking off current in which the engaging contacts will be 35 firmly held together so that accidental release cannot occur and inasmuch as the tines of the plug, and the openings in which they are received, are disposed at a right angle to each other, the insertion of the plug in any other than the predetermined manner is prevented. This arrangement also aids in maintaining the engagement of

the tines with the spring jaw contacts and will avoid the fumbling and consequent wear upon the parts which is occasioned by persons attempting to insert the plugs without giving the matter proper attention. With the present device, it is 5 necessary to bring the plug into a predetermined position before it can be inserted and this insures the proper care on the part of the operator. The device is simple and compact and can be produced at a cost not appreciably greater than the ordinary plugs in common use while the contact will be more efficiently maintained. 10

Having thus described the invention, what is claimed as new is:

A plug comprising a body of insulating material 15 formed with a cable receiving passage extending from front to rear ends of the body and having its forward portion enlarged, the front end of the body being formed with a flat annular surface surrounding the enlarged forward portion of the 20 passage, arcuate conductor plates each having a flat tine extending from one end thereof, a securing screw and a clamping screw extending through opposite end portions of each plate into said body to firmly secure the conductor plates 25 against the annular face of the body, the conductor plates being secured against diametrically opposite portions of the annular face and extending circumferentially of the body with the tines 30 opposite each other, aligned notches being formed in the body between spaced ends of the plates, and a flat bar of insulating material disposed diametrically across the enlarged forward end portion of said passage with its ends seated in said notches and its intermediate portion being formed 35 with wire receiving openings spaced from each other longitudinally of the bar, said bar being disposed obliquely with respect to the tines for defining a relatively large wire receiving chamber for each tine.
